[57] CLAIM

The ornamental design for a chipper/shredder, as shown and described.

DESCRIPTION

FIG. 1 is an end elevational view of a chipper/shredder showing our new design;

FIG. 2 is an opposite end elevational view of the chipper/shredder shown in FIG. 1;

FIG. 3 is a side elevational view of the chipper/shredder shown in FIG. 1;

FIG. 4 is an opposite side elevational view of the chipper/shredder shown in FIG. 3;

FIG. 5 is a side elevational view similar to FIG. 3, showing an alternative embodiment for the chipper chute guard;

FIG. 6 is a top plan view of the chipper/shredder shown in FIG. 1;

FIG. 7 is a bottom plan view of the chipper/shredder shown in FIG. 6;

FIG. 8 is a top plan view of a chipper/shredder showing an alternative embodiment for the hopper;

FIG. 9 is a bottom plan view of the chipper/shredder shown in FIG. 8;

FIG. 10 is a side elevational view of the chipper/shredder shown in FIG. 8;

FIG. 11 is an opposite side elevational view of the chipper/shredder shown in FIG. 10;

FIG. 12 is an end elevational view of the chipper/shredder shown in FIG. 11; and,

FIG. 13 is an opposite end elevational view of the chipper/shredder shown in FIG. 12.

The broken line illustration of an engine is for illustrative purposes only and forms no part of the claimed design.
